UNITED STATES PATENT OFFICE

GEORGE H. PERKINS, OF WELLESLEY, MASSACHUSETTS, ASSIGNOR TO POWDRELL & ALEXANDER, INC., OF BOSTON, MASSACHUSETTS, A CORPORATION OF MASSACHUSETTS

DESIGN FOR A TEXTILE FABRIC

Application filed August 14, 1931. Serial No. 40,850. Term of patent 3½ years.

To all whom it may concern:

Be it known that I, GEORGE H. PERKINS, a citizen of the United States of America, residing in Wellesley, in the county of Norfolk and Commonwealth of Massachusetts, having invented a new, original, and ornamental Design for Textile Fabric, of which the following is a specification, reference being had to the accompanying drawing forming part thereof.

The figure is a face view of the fabric showing my new design.

The motif or unit of the design comprises a cabin and windmill spaced apart, said motif being repeated vertically and horizontally.

I claim:

The ornamental design for a textile fabric as shown and described.

Signed by me at Danielson, in the county of Windham and State of Connecticut, this 7th day of August, 1931.

GEORGE H. PERKINS.
